Patent expires November 14, 1961

4 Claims. (Cl. 137—53)

1

The present invention relates to devices for discharging air or other gases present in conduits or containers containing liquids, and particularly liquids under pressure, such as, for instance, in hydraulic brake conduits, in conduits of alternative pumps under hydraulic control, in conduits of central steam and hot water heating and the like.

It is known that the operation of an installation which is hydraulically controlled is subject to irregularities due to the presence in its conduits of air or gas, and that it is necessary to accomplish an evacuation of such air and gas in order to insure proper functioning of the installations.

All the devices used heretofore for this purpose are subject to certain disadvantages due to the very principle of their operation, and it is the object of the present invention to eliminate these disadvantages.

The device according to the present invention is based on a novel principle. Its operation depends on a difference in pressure which occurs between two zones in communication with each other. One of these zones is also in permanent communication with the medium from which the air or gas is to be discharged. The second zone communicates with the atmosphere by means of a valve, each increase in the pressure prevailing in the medium to be evacuated creating the desired pressure difference which in its turn determines the opening of the valve.

According to one embodiment of the invention the two zones are separated by a wall provided with at least one orifice. According to another embodiment, the two zones are formed in a single unitary space.

The invention will be better understood with the aid of the accompanying drawing which exemplifies illustratively two embodiments of the invention.

In the drawing:

Fig. 1 is a sectional view of a device according to one embodiment of the present invention; and Fig. 2 is a similar sectional view of a device according to a second embodiment.

Referring first to Fig. 1, 1 is the body of an air or gas discharge device according to the invention inserted in a conduit containing a liquid. The device as shown in Fig. 1 comprises two chambers 2 and 3. The chamber 2 communicates permanently and directly with the liquid carrying conduit and the chamber 3 can be brought into communication with atmosphere by means of a gas escape port controlled by a valve 4.

2

The two chambers are separated by a wall 5 provided with two orifices 6 and 7. Two diaphragms 8 and 9 are provided in the bottom of the device and in its upper portion, respectively, said diaphragms being connected by a rod 10 which, in the embodiment shown, passes through a central opening in the wall 5.

According to Fig. 1, the orifice 6 is formed by the play provided between the rod 10 and the central opening in the wall 5. The wall 5 has a conical form and the orifice 7 is made at the lower edge of the cone while the orifice 6 is disposed in the apex of the cone. In this manner the air or the gas which accumulates in the upper portion of chamber 2 passes easily into the chamber 3 through the passage 6, while the orifice 7 facilitates the circulation. The upper portion of the chamber 3 can be brought into communication with the atmosphere through a gas escape port 11 provided in the carrier 12 of the diaphragm 9. The port 11 is normally closed by the valve 4. When an increase in pressure occurs in the liquid carrying conduit, this increase will not be immediately transmitted to the chamber 3, and, consequently, the diaphragm 8 is subject to an excess pressure which causes a displacement of the rod 10 downwardly, thus opening the valve 4 and permitting the air or gas which has accumulated in the chamber 3 after passing the orifice 6 to escape into the atmosphere. As soon as the excess pressure ceases, the rod 10 returns to its normal position and the valve 4 is closed. Thus the device operates at each increase of pressure in the liquid carrying conduit and the discharge of the air or gas is effected automatically. In the case of a hydraulic brake system, the device operates at each operation of the brake so that discharge of air or gas is insured in a perfect and very simple manner.

In the embodiment of the invention illustrated in Fig. 1 the two zones 2 and 3 are separated by a fixed or stationary wall 5. It should be understood that the device could function even in the absence of the wall 5. In effect, the air or gas would accumulate automatically in the upper portion of the chamber 2—3 and the two zones necessary for the operation of the device would be created automatically even without a separation wall. However, this wall insures a better functioning of the device, and, consequently, it is present in the preferred embodiments of the invention. The wall 5 could have any desired shape, but it is preferable to give it a conveniently inclined shape such as, for ex-

ample, that of a cone, as shown in Fig. 1, in order to facilitate the accumulation of air or gas in the uppermost portion of the zone 2 and its passage into the chamber 3.

Fig. 2 illustrates a second embodiment of the invention in which the two zones 2 and 3 are separated by a movable wall 13. In this case, the diaphragms are omitted and the valve 16 is controlled by the movable wall 13. The upper portion of the device is formed by a cover 14 provided with a gas escape port 15. The port 15 is closed by the valve 16 carried on a rod 17 rigid with the movable wall 13. The wall 13 is held in its normal position by a spring 18 which insures closing of the valve. The lower surface of the wall 13 is inclined and one orifice 19 is formed in the highest portion of the wall 13 while another orifice 20 is provided in the lowest portion of said wall. In this manner air or gas which accumulates in the chamber 2 can pass into the chamber 3. As soon as an increase of pressure occurs in the pressure liquid-containing conduit the movable wall 13 is upwardly displaced so as to lift the valve 16, whereupon the air or gas accumulated in the chamber 3 is discharged to the atmosphere.

The operation of the device according to Fig. 2 is based on the same principle as that of the device according to Fig. 1 with the difference, however, that in the arrangement according to Fig. 2 the wall is indispensable because the opening of the valve 16 on each increase of pressure is caused by the displacement of this wall.

It should be understood that the device according to the invention can be used with any conduit or container whatever which contains liquid in order to insure an automatic discharge of air or gas on each increase of pressure in the conduit or container. It is particularly intended to use these devices in connection with the conduits of hydraulic brakes.

It should also be understood that the invention is not limited to the examples shown, and that the air or gas discharge devices according to the invention can be constructed in various different forms without deviating from the spirit of the invention. Particularly, in the case of a device of the type shown in Fig. 1 in which the separating wall is not absolutely necessary, the movable element can be formed in any suitable manner other than by diaphragms. Moreover, the connection between these movable elements can be effected by external means replacing the rod 10. Finally, if a wall is provided, such wall may assume any desired convenient form and the orifice or orifices may be disposed at any point or points desired.

The same applies to the device according to Fig. 2. The movable wall can also assume any convenient form as may the valve, etc.

Finally, it should be understood that the invention relates to hydraulic systems employing liquids under pressure as well as to systems in which the liquid is not subject to any pressure, and in which, according to the invention, suitable means may be provided to insure at predetermined times, the creation of the excess pressure necessary for the operation of the device.

I claim:

1. A device for discharging gaseous impurities from liquid filled systems, comprising a chamber having at its bottom level an entry port

adapted to be connected to a liquid filled system at the highest point thereof, and provided at its top with a gas escape port leading to the atmosphere, valve means including a movable member and normally closing said gas escape port, said chamber being subdivided into a lower and an upper compartment communicating with each other through at least one restricted passage, and a movable element rigid with said movable member of said valve means and having two opposite surfaces exposed to the pressures in said upper and lower compartments, respectively, said surfaces having active areas so dimensioned that the valve means remains closed, regardless of pressure variations in the liquid filled system as long as both compartments are filled with liquid but opens in response to rapid pressure fluctuations in the liquid system and in the lower compartment whenever a cushion of gas has accumulated in the upper compartment.

2. A device as claimed in claim 1, in which said movable element is a piston slideable in said chamber and which serves to sub-divide the same into upper and lower compartments, the surface 25 of said piston facing said lower compartment being inclined from the horizontal, one restricted passage through said piston opening into said lower compartment being provided at the highest point of said inclined surface, and a second restricted passage through said piston opening into said lower compartment being provided at the lowest point of said inclined surface.

3. A device as claimed in claim 1, in which said escape port is formed as a stationary valve seat, 35 and said movable member is a valve cooperating with said seat, said movable member including a piston vertically slideable in said chamber subdividing said chamber into an upper and a lower compartment, a rod projecting from the upper surface of the piston and connecting the piston with the valve and a guide rod projecting from the opposite surface of the piston and passing slidably through a wall of said chamber to the outside, said guide rod having a cross-sectional 40 area equal to that of said valve seat, and a spring acting on said piston to hold said valve normally in its closed position.

4. A device as claimed in claim 1, in which said chamber is subdivided by a stationary transverse 50 wall and said movable element includes two diaphragms closing said chamber at its upper and lower ends, respectively, and a rod connecting said diaphragms, said gas escape port being formed in the upper diaphragm, and a fixed abutment closes said gas escape port when said diaphragms assume their normal positions.
